CLOSURE AND PACKAGE

Philip O'C. White, Chicago, Ill., assignor to White Cap Company, Chicago, Ill., a corporation of Delaware

Application September 18, 1939, Serial No. 295,406

13 Claims. (Cl. 215—44)

This invention relates to packaging, and pertains particularly to a package and closure suitable for use in the preservative packing of food-stuffs or the like.

The general object of the invention is the provision of a simple closure and package appropriate for such uses, which may be supplied to users at low cost, which is effective to seal and preserve the contents in an air-tight condition, and in which the closure is applied in the first instance with facility, will hold its place securely, yet be susceptible of removal, when desired, without involving any mutilation of it, and which, after such original removal, may be adapted for continued use as a tight closure for the receptacle on which it is used.

A particular object of the invention is the provision of a closure cap for use on jars or similar receptacles which have peripheral screw threads or similar closure-retaining elements adjacent their mouths, and which cap is of such character that it may be applied to and hermetically sealed upon such a jar in the first instance simply by pressing it downwardly on the jar mouth after air has been displaced or exhausted from within the jar, and may be removed in the first instance simply by prying it upwardly enough to break the hermetic seal and then lifting it off, and after such removal can be readily adapted or adjusted by the housewife in such fashion that it may be re-applied to the jar and retained thereon and detached therefrom in the manner of a screw cap.

A further particular object of the invention is the provision of a package having a closure which, in the first instance, is held in place merely by atmospheric pressure, yet is readily adaptable or adjustable by the user so that it may be re-applied and held in place as a screw cap, the construction being characterized by features which support the closure skirt against distortion inwardly, thereby to safeguard the original hermetic seal against being broken inadvertently when the skirt of the closure is grasped in the handling of the package.

Screw caps, as closures for packages of food-stuffs and the like which are dispensed piece-meal, are favored by many consumers, housewives for the most part, because they are familiar with the operation of such caps and have confidence in their security, and immediately recognize them as re-seal closures. However, it is recognized by food packers that screw caps require more time for application and sealing on receptacles than do caps of other types, for ex-

ample, types wherein the closure is sealed on the receptacle in vacuo by a simple pressing operation and is subsequently held in place primarily by the external atmospheric pressure. It is likewise true that it is difficult to remove a screw cap which is seated on a rubber gasket from a package from which the air has been exhausted. This is on account of the great resistance to the rotation of the cap which is offered by the high friction between it and the gasket under the external atmospheric pressure. Accordingly, while screw caps are desirable, from the standpoint of the consumer, for purpose of re-sealing, they have serious disadvantages as regards initial application by the packer and original removal by the consumer.

The present invention provides a closure and package which meet the requirements of both packer and consumer and obviate disadvantages referred to above, inasmuch as it is of such character that the packer may apply and hermetically seal it upon a suitable screw-threaded receptacle without screwing it into place, and the housewife may remove it from the evacuated package with facility and without unscrewing it, and, after its original removal, may readily adjust or adapt it so that thereafter it may be re-applied to the receptacle and operated as a screw cap to form an air-tight and securely affixed closure.

Various other objects and advantages of the invention will be pointed out or indicated hereinafter or will be apparent from the following description.

For purpose of aiding in an explanation of the invention, I show in the accompanying drawing forming a part of this specification, and herein-after described, certain forms in which it may be embodied. It is to be understood, however, that these are presented merely by way of illustration and are not to be construed in any fashion for limiting the appended claims short of their true and most comprehensive scope in the art.

In said drawing,

Fig. 1 is a view of an upper portion of a package forming the subject matter of the present invention, same showing some of the parts in elevation and some in section, and serving to illustrate the relationship of the receptacle and one form of closure after the initial application and sealing of the latter upon the former;

Fig. 2 is an elevational view of such closure cap before it is applied to the receptacle in the first instance or after it is originally removed from the receptacle;

Fig. 3 is a detail in the nature of a section on line 3—3 of Fig. 2 but on a considerably enlarged scale;

Fig. 4 is a sectional detail view illustrating the relationship of such closure and the receptacle after the closure has been adapted for cooperation with the receptacle in the fashion of a screw cap and re-applied thereto, as by a user after the package has been initially opened;

Fig. 5 is a diagram illustrating the relationship of some of the parts of the closure cap represented in the preceding figures;

Fig. 6 is a lay-out of an improved threading for the neck of the receptacle;

Fig. 7 is a sectional detail similar to Fig. 4 and illustrating the relationship of parts of a closure cap of the type shown in Figs. 1 to 4 inclusive hermetically sealed on a threaded receptacle of the character illustrated in Fig. 6;

Fig. 8 is a sectional detail similar to Fig. 7 and showing the same closure cap and receptacle but with the section taken at a point intermediate the holding elements;

Fig. 9 is a similar sectional detail illustrating a modified form of closure cap in position on a threaded receptacle but before it is pressed to the hermetically sealed position;

Fig. 10 is a similar sectional detail illustrating the relationship of the form of closure cap shown in Fig. 9 to the receptacle in the operation of applying it thereto as a screw cap, after it has been originally removed from the receptacle and modified by the user;

Fig. 11 is a fragmentary elevational view of a closure cap of the type illustrated in Figs. 9 and 10; and

Fig. 12 is a similar fragmentary elevational view of another modified form of closure cap which contains certain of the features of the type illustrated in Fig. 2 and other features of the type illustrated in Figs. 9 and 11.

The nature of the invention will be most quickly ascertained from the following detailed description of the illustrative embodiments shown in the drawing. The closure cap includes a shell which is preferably formed of a material such as sheet metal having the proper strength, stiffness and ductility. It is shaped with a top 10 and a depending annular skirt 11 which terminates at its lower margin in a rolled annular stiffening bead 12. Retained in the shell, as by being adhesively secured to the top 10, is a sealing gasket 14, which has a certain amount of elasticity but also some plastic quality, as for example, a partially vulcanized rubber compound or a rubber compound containing latex. This gasket occupies a position against the under side of the top 10 adjacent the skirt 11.

At suitable circumferentially spaced locations the skirt is provided with adjustable holding elements of special character. In the embodiments illustrated in Figs. 1 to 5 inclusive, 7 and 12, these are formed by slitting the metal of the skirt along a line 15 extending parallel with the top 10 and re-forming a portion of the metal below said slit, as in the shaded area 16, by pressing it inwardly slightly. The structure is shown on magnified scale in Fig. 3, where it will be seen that the metal immediately above the slit is pressed inwardly slightly and that the upper margin of the re-formed portion 16 is pressed inwardly only a very slight distance beyond the normal outer surface of the skirt. Consequently, a slight shoulder or outwardly overhanging portion 17 is formed immediately

above the slit. In this fashion the raw edges along the slit are effectively covered and concealed.

Any appropriate number of these holding elements may be thus provided, two spaced 180° apart, three spaced 120° apart, or four spaced 90° apart, etc. In the particular example illustrated the slits are the same distance from the top of the shell, but it is to be understood that various other arrangements may be used.

The shell, of course, is proportioned with reference to the receptacle upon which it is to be used, and said receptacle 28, as shown in Fig. 1, is formed with a neck portion 21, preferably of approximately cylindrical form above a peripheral outwardly extending ledge 22, and upon said neck portion 21 are formed suitable retaining elements. These may be in the nature of a plurality of outwardly projecting lugs or ledges 24 arranged at a circumferential distribution corresponding to that of the holding elements of the closure and having their under surfaces pitched or sloping in the circumferential clockwise direction after the fashion of a screw thread. These are conventional ledges or inclines but the retaining elements may be of any of various other forms, such as conventional screw threads, either continuous or plural.

A characterizing feature of the closure is the fact that in its original complete condition, the condition in which it is supplied to the packer and by him applied to the receptacle, it may be applied to the neck of the receptacle and fully seated to sealed position thereon with its holding elements 16 in any position, circumferentially considered, relative to the ledges 24. This is due to the fact that the skirt of the closure is purposely formed on such a radius that it will admit the overall width of the neck, inclusive of the ledges 24, past the holding elements 16 when they are in their initial positions as illustrated in Figs. 1 and 3. In other words, the inwardly displaced portions 16 of the holding elements are not pressed inwardly far enough to interfere with the neck ledges 24, and hence the closure may drop freely onto the receptacle until the gasket seats on the mouth rim.

As a consequence, the closure may be sealed on the receptacle in the first instance by a very simple procedure involving merely the placing of it upon the receptacle neck, either before or after air has been displaced from the head space, then pressing it down so as to intrude the mouth rim of the receptacle into the gasket sufficiently to effect an air-tight sealing contact between them, and then, while so held, subjecting the package to normal atmospheric pressure. As a consequence of the reduction in the internal pressure, the closure is held in place on the receptacle by the external atmospheric pressure in a well known fashion. The parts are so proportioned that when so sealed on the receptacle, the lower margin of the closure is spaced above the ledge 22, approximately as shown in Fig. 1, so as to accommodate the insertion of a prying implement between them, whereby the closure may be forced upwardly sufficiently to break the hermetic seal and admit air into the package. Thereupon the closure may be lifted off freely.

It is thus to be observed that the closure in the first instance may be applied by very simple and economical operations on the part of the packer, and that it may be removed in an unharmed condition by equally simple operations on the part 75 of the consumer. Upon such removal, the gasket

14 remains adhesively secured in the closure cap.

In order to adapt the closure for use in the fashion of a screw cap, the consumer-user is required simply to press the holding elements 16 inwardly to an extent such that at least a part of their upper margins will come within the circumferential area of the ledges 24. This may be done conveniently while the closure is off of the receptacle, simply by pressing inwardly the portions 16 with the tip end of a spoon. The circumferential extent of the slits 15 imposes a practical limitation to the extent to which the parts 16 may be conveniently pressed inwardly, and the shoulder 17 (Fig. 3) forms a stop or guide for the positioning of the implement with which the pressing is done. A suitable legend may be lithographed on the top 10, giving the necessary directions as to the pressing of the holding elements. It is to be observed that in the original pre-forming of the elements 16 they are placed under some compression longitudinally, or in the circumferential direction of the skirt, due to the fact that their upper margins are moved toward a chordal position relative to the arc of the skirt. When they are subsequently displaced farther inwardly by the user so as to move them to positions where they will function as screw lugs, they are moved past the chord line, with the result that the metal of the skirt reacts through them, in their longitudinal direction, to resist their deflection outwardly. In other words, as illustrated diagrammatically in Fig. 5, the chord line *ch* represents a dead-center plane located outwardly from the margin of the inwardly offset holding element 16 and, since the chordal length is less than the length of the holding element, the outward displacement of said element is resisted by the metal of the skirt 11.

Accordingly, when the user has bent the holding elements inwardly as above described, they form inwardly projecting lugs somewhat as illustrated in Fig. 4, suitably spaced circumferentially for cooperation with the receptacle ledges 24 in the customary fashion of screw lugs. The spacing of the slits 15 relative to the top of the cap and the spacing of the inclined lower surfaces of the ledges 24 relative to the mouth rim of the receptacle are selected so that when the closure is screwed onto the receptacle, the mouth rim of the latter will be pressed into the gasket 14, as seen in Fig. 4, so as to form a tight seal, even though the overlying portion of the gasket may have become set in a somewhat thinner shape than it was before the closure was initially applied.

Accordingly, it will be apparent that the closure as thus adapted by the user is appropriate for continued use as a screw closure for the receptacle, in which use it is qualified to hold its place securely and form a tight seal, it being understood, of course, that the metal of the skirt is of such strength and stiffness that the holding elements can suitably withstand the pressure induced by screwing the cap down firmly upon the receptacle. The stiffening bead 12 contributes to stability of the holding elements and resists distortion of the skirt. The form of the holding elements as above described avails of the strength of the metal to the best advantage, as they remain integral with the skirt metal throughout their entire height and they are located below the ledges so that they are in compression and are supported by the stiffening bead and lower skirt metal against the thrust of the ledges.

In instances where the closure cap is of rela-

tively large diameter, such that the skirt may be flexed fairly easily to an out-of-round form by inward pressure at opposite points, as by grasping the skirt of the cap to lift the package, or when the cap shell is made of a metal which is readily flexible, it may be desirable to provide for definitely limiting the extent to which the cap skirt may be flexed inwardly, particularly at points intermediate the holding elements. This may be desirable because of the fact that inward pressure upon the cap skirt sufficient to spring or distort it to an excessively out-of-round form may arch the top 10, and lift the gasket away from the receptacle rim sufficiently to break the hermetic seal. This is particularly likely to happen if the package is thus grasped immediately after the sealing operation, before the contents of the package have been allowed to cool sufficiently to produce a high pressure differential.

One arrangement for providing for the support of the cap skirt is illustrated in Fig. 6. This represents a multiple thread arrangement for the neck of the receptacle, said neck being designated by the numeral 21, and being formed with the pry-off ledge 22. The threads are designated 24', and it will be observed that there is a plurality of them, their upper ends being arranged in circumferential distribution corresponding to the distribution of the holding elements of the cap. From their upper ends, they spiral downwardly to the points 24a, and from those points are continued, in relationships normal to the axis of the neck, as prolongations 24b, which prolongations extend past the upper ends of the threads and for a distance under their higher portions.

As a result of this arrangement of the threads, when the closure is hermetically sealed on the receptacle, abutments will be provided within the entire circumference of the cap skirt and sufficiently close to it and its lower margin to prevent inward flexure of it to an extent such as to arch the top panel and break the hermetic seal. These relationships are illustrated in Figs. 7 and 8, Fig. 7 representing a section through one of the holding elements at a point approximating line 7-7 of Fig. 6, and Fig. 8 representing a section at a point approximating line 8-8 of Fig. 6. While there necessarily must be some clearance between the skirt of the cap and the peripheries of the threads, at some points, in order to permit the cap to go on freely, such clearance is not sufficiently great to permit any material inward distortion of the skirt at its lower edge. Of course, the length of the threads and the extent of their overlapping portions will be varied according to the circumferential size of the receptacle neck, to obtain this result.

For deep skirted caps of medium to large size, for example with an internal skirt diameter of 2.77 in. or more and a skirt depth of $\frac{5}{8}$ in. or so, it is desirable to use substantially thicker sheet metal than is necessary for relatively shallow caps. There are various reasons for this, including the fact that it is easier to apply distorting pressures to larger and deeper skirted caps by hand in the ordinary operations of screwing them onto and taking them off of the receptacle. In embodying the present invention in caps which are made of such heavier and stiffer metal, it may be desirable, in order that the holding elements may be bent inwardly without too much effort, that said elements may be of somewhat modified form. One such modified form is illustrated in Fig. 11, wherein the holding element

is designated at 16', and is in the form of a tongue extending a substantial distance circumferentially of the skirt but only a relatively short distance in the axial direction. This tongue is cut free from the metal of the skirt along its end margins as well as along its upper margin, and remains integral therewith along its lower end. Such a tongue may be bent inwardly by the housewife more readily than can a holding element of the form shown in Fig. 2, and hence is suitable for use in a cap which is made of the stiffer metal. In the forming of such a tongue in the skirt of the cap, it is likely to be displaced inwardly to some extent from the normal internal circumference of the adjacent metal, and this fact, plus the fact that the tongue itself is of substantial thickness, would ordinarily necessitate a considerable clearance between the internal surface of the skirt and the periphery of the screw threads on the receptacle in order to permit the cap to drop freely onto the receptacle neck to a position where the gasket will contact the mouth rim of the latter.

Such excessive clearance or space between the interior surface of the skirt and the periphery of the screw threads is undesirable for various reasons, among them the fact that it permits the cap to be sealed on the receptacle in a considerably eccentric relationship and the fact that it permits distortion of the skirt by inward pressure.

To eliminate these disadvantages, I provide the construction illustrated in Figs. 9, 10 and 11, wherein the cap skirt is made of an internal diameter such that it will drop freely past the periphery of the screw threads of the receptacle, but without leaving a clearance such as to permit any substantial lateral or eccentric shifting of the cap on the receptacle neck. Then, in order to accommodate the necessary inward displacement of the tongues or holding elements, I form the skirt with outwardly embossed portions or panels 25, which are pressed outwardly to an extent somewhat in excess of the thickness of the metal. The tongues or holding elements are slotted out of and offset inwardly from these embossments or panels 25, so that their innermost surfaces lie approximately on the arc of the internal surface of the skirt. This relationship is shown in Fig. 9, from which it will be observed that the internal surfaces of both the skirt and the holding elements are closely adjacent the periphery of the thread. Thus the closure is permitted to drop freely onto the neck of the vessel to the position shown in that figure.

For the purpose of adapting the closure for screw engagement with the receptacle, after its original removal therefrom, the holding elements 16' are bent inwardly, as by pressure from the tip of a spoon or similar utensil, to an extent such that their upper margins fall within a circumference less than that of the thread periphery. In such disposal, the holding elements are adapted to function as screw lugs, and to engage the thread of the receptacle as illustrated in Fig. 10, enabling the cap to be screwed onto the receptacle and be securely retained thereon with its gasket in sealing engagement with the rim of the receptacle. Of course, holding elements of various kinds may be thus formed in the offset panels or embossments 25. In Fig. 12 I show such an arrangement wherein a holding element 16, of the sort illustrated in Figs. 2, 3 and 4, is provided in an embossment or outwardly offset panel 25. Of course, the construction may be varied in

numerous other particulars. For example, the ledges of the receptacle may be made in the form of a continuous screw thread and the holding elements disposed at different distances from the top, appropriate for cooperation with such threads, or the ledges may be formed with non-sloping under surfaces and the holding elements of the closure may be formed with pitched or sloping upper margins for wedging or camming cooperation with them. Hence it is to be understood that in the appended claims the terms "thread" and "screw thread" are used in a generic sense.

What I claim is:

15. A closure cap for use as a slip-on cap and as a screw cap on a receptacle having a peripherally threaded neck, comprising a shell having a top portion with a plastic annular sealing gasket secured in contact with its under surface in position to seat on the mouth rim of the receptacle and form an hermetic seal thereon, and a depending annular skirt of size such as to receive the threaded neck of the receptacle freely and permit the closure to drop downwardly thereon until the gasket contacts the mouth rim, said skirt having pre-formed therein holding elements which are located entirely outside the area of the receptacle neck thread but are displaceable inwardly, by radial pressure applied by hand after the closure is removed from the receptacle, to positions where portions of said holding elements are within the area of the receptacle neck thread so as to cooperate therewith as screw lugs to permit the closure to be screwed onto and off of the receptacle and form a tight re-seal thereon.
20. A closure cap as specified in claim 1 and wherein the skirt is formed immediately adjacent said pre-formed holding elements with external stop portions for facilitating the proper positioning on the holding elements of an implement whereby they may be bent inwardly.
25. A closure cap as specified in claim 1 and wherein the upper margins of the holding elements are defined by slits in the metal of the skirt, and the metal along said slits is displaced inwardly slightly so as to conceal the raw margins.
30. A closure cap as specified in claim 1 and wherein the holding elements are integral with the skirt metal at their ends and along their bottoms and are respectively formed with an upwardly presented margin which is displaceable inwardly beyond the chord line which meets the skirt at the ends of said margin.
35. A closure cap as specified in claim 1 and wherein the skirt is shaped with outwardly offset embossments in which the holding elements are formed.
40. A closure cap as specified in claim 1 and wherein the skirt is shaped with outwardly offset embossments in which the holding elements are formed as upwardly extending tongues.
45. A closure cap as specified in claim 1 and wherein the skirt is shaped with outwardly offset embossments in which the holding elements are formed as upwardly extending tongues located approximately in the normal arc of the skirt.
50. A closure cap for the purpose described comprising a shell made of sheet metal and having a top portion and an annular depending skirt, and a plastic annular sealing gasket secured against the under surface of the top portion adjacent the skirt and adapted to form an her-
55. A closure cap as specified in claim 1 and wherein the skirt is shaped with outwardly offset embossments in which the holding elements are formed as upwardly extending tongues.
60. A closure cap as specified in claim 1 and wherein the skirt is shaped with outwardly offset embossments in which the holding elements are formed as upwardly extending tongues.
65. A closure cap as specified in claim 1 and wherein the skirt is shaped with outwardly offset embossments in which the holding elements are formed as upwardly extending tongues located approximately in the normal arc of the skirt.
70. A closure cap for the purpose described comprising a shell made of sheet metal and having a top portion and an annular depending skirt, and a plastic annular sealing gasket secured against the under surface of the top portion adjacent the skirt and adapted to form an her-
75. A closure cap as specified in claim 1 and wherein the skirt is shaped with outwardly offset embossments in which the holding elements are formed as upwardly extending tongues located approximately in the normal arc of the skirt.

metic seal on the mouth rim of the intended receptacle, said skirt having pre-formed therein adjustable holding elements disposed approximately in the arc of the skirt, the upper portions of said holding elements being displaceable inwardly by radial pressure applied by hand to positions where they may engage thread portions of a receptacle spaced inwardly beyond the arc of the skirt.

9. A closure cap as specified in claim 8 and wherein the skirt is provided at its lower end with a circumferential stiffening bead located adjacent the lower ends of the holding elements.

10. A closure cap for the purpose described comprising a shell formed with a top portion and annular depending skirt, and a plastic sealing gasket secured upon the under side of the top portion adjacent the skirt, said skirt being formed with outwardly offset embossments at locations spaced circumferentially thereof, and portions of the material within said embossments being formed as tongues disposed approximately in the normal arc of the skirt, said tongues being severed from the skirt along their upper margins and remaining integral with the skirt at their lower margins, whereby their upper portions may be displaced inwardly by pressure applied by hand to function as screw lugs.

11. A closure cap as specified in claim 10 and wherein the skirt is provided at its lower end with a circumferentially extending annular stiffening bead adjacent the lower ends of said tongues.

12. A package comprising a receptacle having a neck with a peripherally projecting thread, and a closure cap having a metal shell formed with a top portion and depending annular skirt, a plastic sealing gasket being secured upon the under surface of said top portion adjacent the skirt, said skirt having pre-formed therein adjustable holding elements which are disposed entirely beyond the periphery of said thread so that the closure cap can drop freely onto the receptacle neck to a position where the gasket may seat on the mouth rim of the latter, upper ends of said holding elements being displaceable inwardly by radial pressure applied by hand when the closure is off of the receptacle, to positions where they may engage under the thread and cooperate therewith as screw lugs so as to enable the closure to be screwed into place on the receptacle and press the gasket upon its mouth rim.

13. A package as specified in claim 12 and wherein the said thread is formed in a plurality of sections each having its upper part extending spirally and its lower part extending normal to the axis of the neck, said sections being disposed with spiral upper portions of respective sections overlapping normal lower portions of adjacent sections, said thread lying above the lower limit of the skirt when the closure is seated on the receptacle and having its periphery disposed in proximity with the inner wall of the skirt to prevent substantial inward flexion thereof.

PHILIP O'C. WHITE.
